[57] CLAIM

The ornamental design for the fire starter, as shown and described.

DESCRIPTION

FIG. 1 is an isometric view of a fire starter, showing our new design;

FIG. 2 is a front view, the opposite view being a mirror image thereof;

FIG. 3 is a side view, the opposite view being a mirror image thereof;

FIG. 4 is a top view thereof;

FIG. 5 is a bottom view thereof;

FIG. 6 is an isometric view of a second embodiment of a fire starter;

FIG. 7 is a front view, the opposite view being a mirror image thereof;

FIG. 8 is a side view, the opposite side view being a mirror image thereof;

FIG. 9 is a top view of FIG. 6; and

FIG. 10 is a bottom view of FIG. 6.

FIG.1.

FIG.2.

FIG. 3.

FIG.4.

FIG.5.

FIG. 6.

FIG. 7.

FIG. 8.

FIG. 9.

FIG. 10.
